CHILDREN'S POOL OR SIMILAR ARTICLE

John G. Bowes and John N. Rosekrans, Jr., San Francisco, Calif., assignors to Kransco Manufacturing, Inc., San Francisco, Calif., a corporation of California

Filed Dec. 18, 1964, Ser. No. 83,079

Term of patent 14 years

(Cl. D34—5)

FIG. 1.

FIG. 3.

FIG. 2.

FIG. 4.

FIG. 1 is a top plan view of a children's pool or similar article showing our new design;

FIG. 2 is a bottom plan view thereof;

FIG. 3 is a perspective view of one side thereof; and

FIG. 4 is a perspective view of the other side thereof. The dominant features of our design reside in the full line portion of the drawings.

We claim:

The ornamental design for a children's pool or similar article, as shown and described.
